UNITED STATES PATENT OFFICE.

HARRY E. McKECHNEY, OF ROCHESTER, NEW YORK.

NOZZLE FOR HOSE.

SPECIFICATION forming part of Letters Patent No. 772,910, dated October 18, 1904.

Application filed April 27, 1904. Serial No. 205,157. (No model.)

To all whom it may concern:

Be it known that I, HARRY E. McKECHNEY, of Rochester, in the county of Monroe and State of New York, have invented a new and useful Improvement in Nozzles for Hose, which improvement is fully set forth in the following specification and shown in the accompanying drawings.

My invention is an improved hose-nozzle, the same being hereinafter fully described, and more particularly pointed out in the appended claims.

The main object of my present invention is to produce an improved nozzle for hose, by means of which the issuing stream of water may be instantly shut off when occasion demands it.

Other objects and advantages of the invention will be brought out and made to appear in the following specification, reference being had to the accompanying drawings, which, with the letters of reference marked thereon, form a part of this specification.

Figure 1 is a side elevation of my improved nozzle with the operating-lever turned away. Fig. 2 is another side elevation of the nozzle seen as indicated by arrow 2 in Fig. 1, a part of the lever being broken away. Fig. 3 is a central longitudinal section of the stopper, taken on the dotted line 3 3 in Fig. 8, the ball being shown partly in elevation. Fig. 4 is a central longitudinal section of the main parts of the nozzle, taken on the dotted line 4 in Fig. 2. Fig. 5 is a plan of the device 35 or end view seen as indicated by arrow 5 in Fig. 1, parts being broken away and the section being as on the dotted line 5' in said Fig. 1. Fig. 6 is a view at the base of the stopper seen as indicated by arrow in Fig. 3, further showing the construction. Fig. 7 is a side elevation of the barrel or middle section of the nozzle seen as indicated by arrow 7 in Fig. 1, further showing the device, parts being shown in various positions by full and dotted lines. Fig. 8 is a plan of the stopper with a part of the ball broken away. Fig. 9 is a central longitudinal section of the base-piece of the nozzle, taken on the dotted line 9 9 in Fig. 5, showing the stopper in place within and 50 lower parts of the barrel. Figs. 3 and 5 to

9, inclusive, are drawn to various scales larger than that of Figs. 1, 2, and 4.

Referring to the drawings, A is the base-piece of the nozzle, adapted to be removably connected with the coupling on the end of 55 the hose in the usual manner.

B is the barrel of the nozzle, and C the tip, made slightly conical and threaded onto the end of the barrel B in the usual manner against a ring *x* of packing and made temporarily rigid with the barrel, the latter being adapted to slide longitudinally through the reduced part or neck *a* of the base-piece A.

A ring D is threaded on the neck of the base-piece, said ring being hollow or formed 60 with an inner annular chamber *b*, Fig. 4, in which to receive fibrous packing material *c*, pressed against the conical end *d*, Fig. 9, of the base-piece to prevent leaking between the joined parts. The ring D is formed with a 65 bifurcated standard *f*, Figs. 1, 2, 5, and 7, its parallel upwardly-extended branches *e* serving to hold, respectively, the ends of a bent or U-shaped lever E, provided for controlling the position of the barrel B in the base part 70 A. The branches of the lever are on opposite sides of the barrel, the latter being provided with two pairs of lateral projections or lugs *g* adjacent to the respective branches of the standard *f*, the two lugs of each pair 75 being separated by a space *i*, the lever having inwardly-projecting pins *h* *h* engaging in the spaces *i* *i* of the lugs, as clearly shown in Fig. 1. The lugs are transverse of the barrel, the lower one of each pair being the 80 stouter, the pins *h* *h* of the lever moving transversely between the lugs of the pairs as the lever is turned on its fulcrum-bearings *k* *k*, threaded in the heads of the branches *e* *e* of the standard *f*.

It will be understood that by turning the lever E upward toward the tip C or downward toward the base A, as indicated in Fig. 7, the barrel B will be correspondingly shifted in longitudinal directions in its bearing *l* 85 in the neck of the base-piece A, as shown by the positions indicated by full lines and dotted lines in the figure. As clearly shown in Fig. 5, the ends of the four lugs *g* adjacent to the standard *f* are in a longitudinal plane 90

parallel with but at one side of the axis of the nozzle, and from said figure and Fig. 2 it will be further seen that the adjacent faces of the branches of the standard *f* coincide with said plane. On account of this construction and arrangement of the coacting parts the standard constitutes a guide for the lugs during the longitudinal movements of the barrel above described, causing the barrel to move truly longitudinally and without turning in the base-piece A. The construction is also such that the lugs are always in engagement with the standard and controlled by it, the upper ends of the branches *e e* next the lugs being extended or carried out to form right angles, as shown in Figs. 2 and 5.

The base-piece A is formed with an internal thread *m*, Fig. 9, at its lower end to turn onto the correspondingly-threaded hose-coupling when connecting the nozzle with the hose. Above the threaded part *m* the part A is formed with a cylindrical chamber *n* mainly for the purpose of holding a packing-ring *y*. Above the chamber *n* the base part A is formed with an internal circular-threaded seat *o* for receiving the threaded circular part or ring *p* of a stopper F, Figs. 3, 6, 7, 8, and 9, the seat *o* being less in diameter than the threaded part *m*. When the stopper F is put to place in the base-piece A, it is inserted upward through the large open end of the base-piece, and when screwed home or to place against the circular shoulder *z* of the base-piece the lower surface of the ring *p* of the stopper is in the plane of the upper shoulder or annular wall *a'* of the chamber *n*, as clearly appears in Fig. 9. The ring of packing *y* bears evenly against the wall *a'* and the base-ring *p* of the stopper, the inner end of the hose-coupling pressing the packing-ring *y* on the lower side when the nozzle is screwed firmly to place upon the hose.

Besides the threaded ring *p* the stopper F comprises a central inverted conical body or part *r*, joined in one piece with the ring *p* by radial wings *s* and an element *t* of yielding material, as india-rubber, with means *u* for holding the part *t* in place. The part *t* is commonly a ball of india-rubber or similar yielding packing material, as shown, the upper part of the body *r* being hollowed out to receive the ball, as shown in Fig. 3. The holding-bolt *u* pierces the ball diametrically, having its inner end threaded in the part *r* with a washer *v* and threaded nut *w* above the ball, the bolt being coaxial with the barrel B of the nozzle. When the stopper is in place in the base-piece A, as shown in Fig. 9, it is coaxial with the nozzle as a whole, and in position to meet or receive the lower hollow end of the barrel when the latter is carried down by the lever E, as above described. Thus the stopper serves to close the inner end of the barrel when the latter is brought down against it by the operating-lever E and wholly

stops the flow of water outward through the nozzle until the lever is again turned upward to the position shown in Figs. 1, 2, and 7. As the barrel B is pressed with considerable force against the stopper by the lever E to insure a complete stopping of the stream issuing from the nozzle, the lower lug *g* of each pair is made stronger than the upper lugs, the pressure of the lever against the upper lugs being only that sufficient to slide the barrel upward through the ring of packing *c*.

I form the neck *a* of the base-piece A with an internal chamber *b'*, Figs. 4 and 9, which serves to arrest and hold extraneous or sedimental matter, as sand and grit, held in the flowing water and prevent said matter from entering the packing-chamber *b* and fouling the packing therein.

By giving to the central part *r* of the stopper F the form of an inverted cone, as shown, I obtain at its upper end a sufficiently broad cup or holder for the yielding part *t*, while the apex of the cone being turned downward offers the least resistance possible to the stream of water flowing outwardly under pressure through the nozzle. This manner of forming the part *r* is important, as it not only affords both the advantages stated, but it also facilitates the work of constructing the part in the matter of molding and drawing the pattern from the sand. The wings *s*, projecting from the central part *r*, are usually three in number, as shown, and equally spaced, their lower ends being reduced to knife-edges for the purpose of presenting the least resistance to the onrushing water as it emerges from the end of the hose and enters the nozzle.

What I claim as my invention, and desire to secure by Letters Patent, is—

1. A hose-nozzle consisting of a base-piece a barrel and a tip joined, the barrel being adapted to move longitudinally within the base-piece, a stopper comprising a removable ring with inverted conical part and a yielding ball seated on and secured to the conical part, secured in the base-piece, and means having loose and movable connection with the barrel for moving the barrel with reference to the stopper.

2. A hose-nozzle consisting of a base-piece a barrel and a tip joined, the tip being removably connected with the barrel and the latter adapted to move longitudinally within the base-piece, a stopper comprising a removable and adjustable ring with inverted conical part and a yielding ball mounted on and secured to said conical part in the base-piece, and means on the base-piece and having loose and movable connection with the barrel for shifting the barrel endwise.

3. A nozzle for hose, consisting of a middle part and two end parts coaxially joined, the middle part being rigidly joined to one said end part and longitudinally movable in the other end part, a stopper comprising a remov-

- able and adjustable ring with inverted conical part and a yielding ball mounted on and secured to said conical part held by one end part to coact with the middle part, and means 5 having loose and movable connection with the barrel to move said middle part toward and from the stopper.
4. A hose-nozzle comprising a base part or piece a barrel and a tip joined, the barrel being adapted to move longitudinally within the base part, a stopper comprising a removable and adjustable ring with inverted conical part and a yielding ball mounted on and secured to said conical part in the base part, and a lever 15 having loose and movable connection with the barrel to move the barrel.
5. A hose-nozzle comprising a base part or piece a barrel and a tip joined, the barrel being adapted to move longitudinally within the 20 base part, a stopper comprising a removable and adjustable ring with inverted conical part and a yielding ball mounted on and secured to said conical part in the base part, a ring on the base part, and a lever carried by the 25 ring having loose and movable connection with the barrel and adapted to control the barrel.
6. A nozzle for hose, having three hollow parts or sections joined coaxially one between 30 the other two in a line, the middle part being movable within one extreme part, an element movable on said extreme part, a lever carried by said element to loosely and movably engage the middle part, and a stopper comprising 35 a removable and adjustable ring with inverted conical part and a yielding ball mounted on and secured to said conical part in said extreme part to coact with the middle part.
7. A nozzle for hose, having three hollow 40 parts or sections joined coaxially one between the other two in a line, the middle part being movable within one extreme part, an element movable on said extreme part, a U-shape lever for controlling the middle part, carried 45 by said movable element and having its branches on opposite sides of the middle part and loosely and movably engaging the latter, and a stopper comprising a removable and adjustable ring with inverted conical part and a 50 yielding ball mounted on and secured to said conical part held by said extreme part to coact with the middle part.
8. A nozzle for hose, having three hollow 55 parts or sections joined coaxially one between the other two in a line, the middle part being movable within one extreme part, a ring formed with a standard mounted on said extreme part, a ring with inverted conical part adjustable in the extreme part and a yielding 60 ball mounted on and secured to the conical part, a bent lever with ends on opposite sides

of the middle section and pivotally joined to the standard, projections on the middle section and means on the lever to engage loosely and movably between said projections. 65

9. A hose-nozzle comprising a base part a barrel and a tip joined, the barrel being between the tip and the base part and longitudinally movable in the latter, a stopper having an inverted conical part and a yielding element mounted on and secured to said conical part to coact with the barrel, and means having loose and movable connection with the barrel to move the barrel in directions toward and from the yielding part. 70

10. A nozzle for hose, having three main hollow parts or sections joined one between the other two, the middle section being longitudinally movable within one extreme section, a stopper with yielding element secured thereto and held removably within said extreme section, and means having loose and movable connection with the middle section for moving the middle section, all said main hollow sections and the stopper being coaxial. 80

11. A hose-nozzle having three hollow sections joined coaxially the middle section being longitudinally movable within one extreme section, a stopper in said extreme section having a threaded ring and central part rigidly 90 connected, and a yielding part mounted on and secured to said conical part to receive said middle section held by said central part of the stopper, and means having loose and movable connection with the middle section for moving said middle section against the stopper. 95

12. A hose-nozzle comprising a base-piece with reduced neck and internal thread at its larger end, internal threaded seat and intermediate cylindrical chamber, a threaded ring 100 engaging in said seat, an inverted conical part integral with said ring, a ball of yielding material seated on said conical part, and means securing said ball to said conical part.

13. A hose-nozzle, comprising a base-piece 105 with reduced neck and internal thread at its larger end, an internal threaded seat and an intermediate chamber, a threaded ring engaged in said seat, an inverted conical part and radial wings integral with said conical part, said conical part being hollowed out, a ball of yielding material seated in the hollowed 110 part of the conical part, and means passed through the ball and securing the same to the conical part. 115

In witness whereof I have hereunto set my hand, this 25th day of April, 1904, in the presence of two subscribing witnesses:

HARRY E. MCKECHNEY.
